UNITED STATES PATENT OFFICE.

FRANS O. ALBERTSON, OF SIOUX CITY, IOWA, ASSIGNOR TO ALBERTSON & COMPANY, INC., OF SIOUX CITY, IOWA, A CORPORATION OF IOWA.

REAMER-GRINDING MACHINE.

Application filed June 30, 1926. Serial No. 119,552.

My invention relates to grinding machines. More particularly, my invention contemplates the provision of a reamer grinding attachment for small garage type 5 grinding machines.

It is an object of my invention to provide a simple attachment for grinding machines whereby reamers and similar tools may be quickly and accurately ground.

10 A further object of my invention is to provide improved means for maintaining the reamer in proper position relative to the abrasive wheel to obtain a practical working clearance.

15 A further object is to provide an improved attachment for a small portable grinding machine which is simple in construction, may be economically manufactured and which may be efficiently operated by relatively unskilled workmen, to accurately sharpen reamers and similar tools.

Other objects will appear from the following description, reference being had to the accompanying drawings, in which

20 Fig. 1 is a perspective view of the reamer grinding attachment, showing a reamer in position to be ground.

25 Fig. 2 is a plan view of the grinding machine with the reamer grinding attachment positioned thereon.

30 Fig. 3 is a perspective view of a gauge employed in adjusting the tooth rest to obtain the proper clearance.

35 Fig. 4 is a vertical section taken on the plane represented by the line 4—4 of Fig. 2.

Fig. 5 is a similar section taken on the plane represented by the line 5—5 of Fig. 2.

The grinding machine proper may be of any suitable construction, but is preferably 40 of the type as shown and described in my co-pending application, Serial No. 718,713, filed June 9, 1924. As shown in Fig. 2, the grinding machine consists of a base casting 11 upon which a motor 12 and emery wheel 13 are mounted, the mounting for these parts being adjustable relative to the base 11. The emery wheel 13 is carried at the end of a shaft 14 which is rotatable in the bearing 15 and which at its other end carries a pulley 16. The pulley 16 is driven by belt 17 which runs over a pulley 18 secured to the motor shaft. An upwardly extending bracket 19 is horizontally bored to receive a rod 21 at the end of which the

emery wheel guard 22 is fixed. The rod 21 is held in adjustable position in the bracket 19 by set screw 23.

A chuck 24 is mounted on a plate 25, which may be moved toward and away from the emery wheel 13. The chuck 24 is also adjustable through an arc, to lie at any desired angle to the plane of the emery wheel 13 so as to be adapted to hold drills, valves and similar articles against the emery wheel at any desired angle. Thus far, I have described the grinding machine proper, in order that the nature of my invention, which consists of an attachment to this machine, may be more readily understood.

The attachment comprises a mounting 70 plate 26 which may be secured to the plate 25 by means of a bolt 27 which passes through the plate 25 and through a suitable drill hole 28 formed in the mounting plate 26. The mounting plate has a downwardly 75 projecting guide 29 which fits into a complementary groove formed in the upper surface of the plate 25, so as to prevent relative rotation between the plates 26 and 25. A pair of cylindrical guides or ways 31 and 32 are secured to lugs 33, 34, 35 and 36 which project upwardly from the mounting plate, by any suitable means such as screws (not shown). A carriage 37 is slidable over the ways 31 and 32 resting thereon at three 80 points. A projection 38 having a machined surface bears upon the way 31 while a pair of machined guides 39 and 41 formed integral with the carriage 37 fit over the way 32. The carriage has a pair of longitudinal 85 slots 42 and 43 adapted to receive the various attachments, as will hereinafter be described. The upper surface has a longitudinal groove 44 which extends the full length of the carriage and serves as a guide for the 90 attachments. The bottom of the carriage is reinforced by longitudinal ribs 45 which extend along each side of the slots 42 and 43 and also serve as means to prevent the rotation of T-headed bolts, by means of which 95 the various attachments are secured to the carriage. The carriage is slidably secured to the ways by means of a clamping member 46 which has machined surfaces 46^a and 46^b adapted to contact with the lower surfaces of ways 31 and 32, respectively. A stub shaft 48 is pivotally carried in a pair of lugs 49, on the clamping member 46,

This shaft is diametrically tapped to receive a fillister head cap screw 50, the head of which fits in a recess 51 in the carriage. It will be apparent that upon tightening the 5 cap screw 50 the clamping member 46 will be drawn upwardly, but that due to the fact that the clamping force acts through the centrally positioned shaft 48 the pressures exerted at the surfaces 46^a and 46^b are equalized. Lug 52 depending from the carriage 37 fits between the upwardly projecting lugs 49 of the clamping member 46 and thus causes the clamping member to slide along the ways with the carriage. A set screw 53 10 acting through a plug 54 is provided to hold the cap screw 50 in adjusted position. A guard 55 depends from the rear edge of the carriage 37, being secured thereto by means of machine screws 56 threaded into 15 the guide lugs 39 and 41. This guard prevents the emery dust and other foreign matter from being thrown against the ways.

The carriage 37 at the ends of its forward edge carries a pair of lugs 57 and 58, which 20 are longitudinally drilled to receive the headed limiting stops 59 and 61, the stops being adjustably secured to the lugs by means of suitable set screws 62. The heads of these 25 stops are adapted to engage the ends of the way 31 and thus limit the extent of movement of the carriage relative to the way. The various attachments which may be adjustably positioned on the carriage 37 will now be described. The tail stock comprises 30 a bracket 63 which has a machined bottom surface resting on the upper machined surfaces of the carriage and has a suitable guiding projection 64 fitting within the groove 44 of the carriage. The bracket is secured 35 to the carriage by means of a T-headed bolt 65 extending through the bracket and the slot 42 of the carriage, the head of the bolt being prevented from turning by the ribs 40. The bracket carries a center 66, the 40 position of which may be adjusted and secured in adjusted position by set screw 67. This center will be termed the fixed center and is adapted to extend within the usual 45 countersunk centering hole at the end of the 50 reamer shank. The other end of the reamer 68 is held in an adjustable center which will now be described.

As best shown in Fig. 4, the adjustable center comprises a base plate 69 having a 55 downwardly projecting guiding lug 71 which fits in the groove 44 in the carriage 37. The adjustable bracket 72 is mounted for sliding movement relative to the base plate 69 in a direction perpendicular to the ways. The 60 bracket 72 has an elongated slot 73 through which the stud 74, which is threaded into the base plate 69, passes. A suitable nut 74^a and washer 74^b are provided for clamping the bracket 72 in adjusted position on 65 the base plate 69. A micrometer adjusting

screw 75 is threaded in the bracket 72, being 70 rotatably mounted in a plate 76, and held against axial movement therein by a squared collar 77, pressed over or formed integral with the screw, and a sleeve 78. The plate 76 is fixed to the bracket 72. Sleeve 78 is held in abutting engagement with collar 77 by a knurled nut 79 threaded upon screw 75, the nut also serving to clamp a dished indicating dial 81 between it and the sleeve. 75 The knurled nut 79 preferably has a squared portion 83 so that these parts may be easily and securely clamped together. The dial 81 is suitably graduated, the graduations being adapted to be brought in register with a 80 scratch mark upon the top surface of the plate 76. The sides of the plate 69 and the bracket 72 have marks O—O (Fig. 1) to indicate the normal position of the bracket. The rear end of the bracket 72 carries a centering pin 84 which may be secured in adjusted position by the set screw 85. The base plate 69 has a side lug 86 (Fig. 2) which is drilled to receive a T-headed bolt 87 extending through the slot 43 in the carriage 90 and thus serves to secure the adjustable center assembly to the carriage in any desired position along the slot.

A tooth rest bracket 88 (Fig. 1) may be secured in adjustable position on the carriage 95 37 by means of a T-headed bolt 89 in a manner similar to that employed in securing the centering brackets. The upper end of this bracket is horizontally drilled to receive a rod 91 which may be secured in adjusted 100 position by means of a set screw 92. The end of the rod 91 is enlarged and diametrically drilled to receive the tooth rest 93 which may be shifted relative to the rod 91 and secured in any desired position by set 105 screw 94 threading into the end of the rod 91. The tooth rest 93 comprises a cylindrical portion which is slideable in the rod 91 and a flattened guide strip 95 which is fixed 110 in the cylindrical portion. This strip is 115 preferably made of hardened steel and has its lower end conformed to serve as a guide for the cutting edges of the reamer, as will later be described.

If desired, the bracket 88 may be eliminated and the tooth rest 93 supported from a bar 96 (Fig. 2) which is secured to the rod 21 by means of a set screw 97 and is drilled and slotted in a horizontal plane so that the rod 91' may be clamped therein by tightening of the screw 98.

In Figure 3 I have shown a gauge 99 which may be used to adjust the height of the tooth rest 93. The bottom surface of this gauge is finished and is adapted to rest upon the upper plane surface of the carriage 37. The end of the gauge bar 99 has a hardened plate 100 secured thereto. The upper edge of this plate serves as the edge upon which the end of the guide strip 95 is positioned 115

when adjusting the height of the tooth rest 93. The upper edge of the plate 100 is slightly above the horizontal plane passing through the centers 84 and 66 so that the 5 tooth rest will cause the cutting edge of the reamer to be positioned to obtain a practical working clearance. A dog 102 is provided with a plurality of set screws 103 by means of which the dog may be secured to the shank 10 of the reamer. When the reamer is held between the centers it may be freely turned by manual rotation of the dog 102.

Although the operation of the attachment above described may have appeared from the 15 description, a brief résumé of the sequence of operations will be given. The reamer grinding attachment is first secured to the grinding machine by tightening the nut on the bolt 27. In grinding straight reamers 20 the tooth rest bracket 88 is preferably employed while the tooth rest supporting bar 96 is necessary in grinding spiral reamers. The proper tooth rest bracket is attached and the tooth rest positioned at the proper 25 height as determined by the gauge 99. The fixed and adjustable centers are then properly positioned along the carriage 37 and the reamer to be ground inserted in position between the centering pins, the dog 102 having first been secured to the shank of the reamer. The limiting stops 59 and 61 are then adjusted so that the carriage will travel a sufficient distance to permit the abrasive 30 wheel to grind the desired length of the cutting edges of the reamer. The adjustable center is set so that the "O" marks on the base plate 69 and bracket 72 coincide. The tooth rest engages the forward surface of one of the cutting edges of the reamer. The 35 set up being ready for the grinding operation, the motor switch is turned "on" and the abrasive wheel brought up against the reamer to take the desired "cut." The operator preferably grasping the dog in his 40 left hand and one of the brackets in his right, proceeds to slide the carriage back and forth on its ways, in the meantime holding the forward surface of the cutting edge of the reamer being ground against the end 45 of the tooth rest 95. The adjustable center may be positioned by means of the micrometer screw to secure the desired taper upon the cutting edges of the tapered reamers and several cuts taken to obtain the required lead. 50 If a spiral reamer is being ground (Fig. 2), the operator will, of course, rotate the reamer in the centers so as to maintain the forward surface of the cutting edge in firm contact with the end of the tooth rest as 55 the reamer is moved longitudinally past the grinding wheel. The guide strip 95 is sufficiently resilient so that after one of the edges has been ground the next cutting edge may be turned past the tooth rest so as to place it in position for grinding. In grinding 60

expansion reamers, the expansion screw of the reamer is removed and a large conical headed center 105 (Fig. 1) is inserted in place of the expansion screw.

It will be seen that the grinding attachment of my invention affords a simple and inexpensive machine for accurately and quickly grinding reamers of various types. The parts may be quickly set up and removed from the grinding machine, and the attachment may conveniently be stored away when not in use.

While the form of mechanism herein shown and described is admirably adapted to fulfill the objects primarily stated, it is to be understood that it is not intended to confine the invention to the one form of embodiment herein disclosed for it is susceptible of embodiment in various forms, all coming within the scope of the claims which follow.

I claim—

1. In a machine of the class described, the combination of a mounting plate, a pair of parallel spaced cylindrical ways secured thereto, a carriage slidable over said ways, and means for securing said carriage to said ways comprising a clamp having a pair of upwardly extending lugs adapted to fit a downwardly projecting lug on said carriage, a shaft passing through said clamp lugs and rotatable therein, and a cap screw seated in said carriage and threaded diametrically through said shaft whereby said clamping member may be drawn toward said carriage, said shaft forming an equalizing means to distribute the clamping force between said ways.

2. In a reamer grinding machine, the combination of a mounting plate adapted to be attached to a grinding machine; spaced upwardly extending lugs at each end of said plate; parallel cylindrical guides carried by said lugs; a carriage mounted on said guides and adjustable thereon, the under side of said carriage being angularly grooved adjacent one edge to engage one of the guides, and formed adjacent its other edge with a plane supporting surface adapted to rest upon the other guide; a clamping member beneath said guides; upwardly projecting lugs on said clamping member; a stub shaft carried by said lugs; and screw means passing through said carriage and stub shaft for clamping the carriage upon the guides.

3. An attachment for grinding machines comprising a mounting plate, a pair of parallel cylindrical guides mounted on said plate and spaced above the upper surface thereof intermediate their ends, a slide carried on said guides, the under surfaces of said slide adjacent one of its edges being formed with a plane bearing surface for contact with one of the guides, and adjacent its opposite edge with spaced lugs, angularly grooved

for contact with the other guide whereby the slide will be supported at three lines of contact with the guides; a clamping member for the slide comprising a plate adapted to contact the under surfaces of said guides and bridge the space therebetween, upwardly extending lugs on said clamping member, a stub shaft carried by said lugs axially of the clamping plate, and means passing through said shaft and slide for holding the slide in contact with the guides.

In witness whereof, I hereunto subscribe my name this 26 day of June, 1926.

FRANS O. ALBERTSON.
